(57) **CLAIM**

The ornamental design for a yoga block and strap combination apparatus, as shown and described.

DESCRIPTION

FIG. 1 is a front, top, right side perspective view of a yoga block and strap combination apparatus in accordance with the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front, top, right side perspective view of another embodiment of a yoga block and strap combination apparatus in accordance with the new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The portions shown in broken lines form no part of the claimed design.

The claimed design is shown with a symbolic break in its length. The appearance of any portion of the article outside of the symbolic break forms no part of the claimed design.

1 Claim, 14 Drawing Sheets
